BUN SLICER

Miles Edward Eever, Anaheim, Calif.

Application January 18, 1934, Serial No. 707,179

2 Claims. (Cl. 146—72)

This invention relates to slicing machines and pertains particularly to a machine or device designed primarily for restaurant use for slicing or splitting buns.

5 The primary object of the present invention is to provide a simple and easily operated device by means of which buns such as are served in lunchrooms and restaurants may be easily and quickly split or sliced horizontally into two or 10 more parts.

A further object of the invention is to provide a device for splitting buns, which can be operated without the user running any risk of cutting himself.

15 A still further object of the invention is to provide a bun slicer or splitter by means of which the bun, after being placed in the device, may be discharged in split condition directly onto a receiving plate.

20 The invention will be best understood from a consideration of the following detailed description taken in connection with the accompanying drawing forming part of this specification, with the understanding, however, that the invention 25 is not confined to any strict conformity with the showing of the drawing but may be changed or modified so long as such changes or modifications mark no material departure from the salient features of the invention as expressed in the appended claims.

In the drawing:—

Figure 1 is a view in top plan of the device embodying the present invention, the proportion of the same being broken away to more clearly show interior construction.

Figure 2 is a cross sectional view taken on the line 2—2 of Figure 1.

Figure 3 is a sectional view taken on the line 3—3 of Figure 1.

40 Referring to the drawing wherein like numerals of reference designate corresponding parts throughout the several views, the numeral 1 indicates a portion of a table, bench or counter, to which the device embodying the present invention may be and is shown applied. The device embodying the present invention is indicated generally by the numeral 2 and comprises an elongated rectangular housing having the top and bottom walls 3 and 4, respectively, the side walls 5 and 6, and one end wall which is indicated by the numeral 7. Extending longitudinally of the side wall 6 and preferably forming an integral part thereof, is a lateral flange 8 which is provided with suitable openings or apertures 55 through which securing screws 9 may be passed

for fastening it to the top of the supporting body 1 adjacent the edge thereof so that the wall 6 may be positioned against the edge of this body.

Adjacent the closed end of the housing, the bottom wall 4 is cut away to provide the outlet or discharge opening 10 and adjacent the opposite end the top wall 3 is cut away or terminated short of the adjacent end of the housing to provide the entrance opening 11 by means of which the buns are placed in the housing.

10 In addition to terminating short of one end of the housing, the top wall 3 also terminates along one longitudinal edge short of the side wall 6 so that there is thus formed the longitudinal top opening which is bordered by the top wall edge 15 12, which at one end opens into the entrance opening 11 of the housing.

The wall 5 has an opening 13 therein through which there extends into the interior of the housing the knife 14. This knife at its outer 20 end has a downturned portion 15 which is secured against the outer face of the wall 5, while the blade extends inwardly through the opening 13 obliquely of the housing and to a point adjacent the wall 6 which may be referred to as the 25 back wall. The edge of the knife 14 is directed toward the end of the housing into which the inlet opening 11 opens so that a bun, when drawn through the housing in the manner about to be described, will be moved against the cutting edge 30 of the knife and after passing the same will be discharged through the opening 10.

35 Disposed within the housing is a pusher, which is indicated as a whole by the numeral 16. This comprises a band of material having a straight portion 17 and a semi-circular portion 18 into which one end of the straight portion merges. This band of material is disposed on edge in the housing and is of a width substantially equal to the depth of the housing or the distance between 40 the top and bottom walls 3 and 4, and the semi-circular portion 18 is of a diameter substantially equal to the interior width of the housing or the distance between the walls 5 and 6.

45 The pusher device 16 is disposed in the housing with the straight portion 17 thereof positioned against the wall 6 and the free end of the semi-circular or arcuate portion 18 adjacent the wall 5 with the concave side of the curved portion directed toward the end wall 7. This 50 curved portion 18 is provided with the slot 19 which extends substantially throughout its length, thus dividing the portion into two parts and through this slot, the blade 14 passes in the operation of the pusher.

Disposed across the opening between the edge 12 of the top wall and the wall 6, is a plate 20 which has an integral downturned side portion 21 which overlies the outer side wall 6, and a 5 spacer member 22 is disposed beneath the plate 20 and upon an inwardly projecting flange or lip 23, which forms a part of the portion 17 of the pusher 16. Through these elements 20, 22 and 10 23, is passed a screw or bolt 24, which passes through and secures to the top of the plate 20 the knob or handle 25 by means of which the movement of the pusher 16 backward and forward in the housing is effected.

While there has been illustrated and described 15 a single knife disposed in and obliquely of the housing, it is not, of course, to be limited to the use of one knife, as it is obvious that two or more knives may be employed.

In the use of the present device, the pusher 16 20 is moved toward the end of the housing opposite that through which the opening 10 opens, in the present case, to the right, so that the portion 18 of the pusher will be disposed beneath the opening 11. The bun or other body to be sliced is 25 then placed on the bottom 4 within the convex portion of the pusher and the operator then moves the pusher to the opposite end of the housing by means of the knob 25. This operation causes the bun to be moved against and along 30 the edge of the knife 14 which passes therethrough and through the opening 19 of the pusher element, thus slitting the bun horizontally and after being slit, the bun is moved onto the point where it will drop out through the opening 10 in 35 the bottom wall, so that by holding a plate beneath this opening, a bun will be discharged thereonto in sliced condition.

I claim:—

1. A slicing device comprising an elongated 40 housing having top, bottom and side walls, said

top wall having an opening at one end of the housing and said bottom wall having an opening at the opposite end of the housing, said top wall further having an opening longitudinally of the housing, a knife disposed within the housing obliquely thereof and with its cutting edge directed toward the end adjacent the top wall opening, an arcuate body disposed within the housing between the side walls and having a slot for the passage of said knife, said arcuate body further 10 having a straight portion disposed against the side wall adjacent the longitudinal opening, and means slidably longitudinally of the top wall and engaged with the straight portion of the arcuate 15 body for effecting the movement of the latter longitudinally through the housing.

2. A slicing device, comprising an elongated body having top, bottom and side walls, said top wall having an opening at one end of the housing 20 and said bottom wall having an opening at the opposite end of the housing, one of said walls having an opening therein extending longitudinally of the housing, a knife disposed within the housing obliquely thereof and horizontally 25 between the top and bottom walls and having its cutting edge directed toward the end of the housing adjacent the top wall opening, a body disposed within the housing and extending across the width thereof and having a slot for the passage of said knife, a member mounted upon the 30 housing for movement longitudinally therealong over said longitudinal opening of the said one of the walls, a handle carried by said member, and a connection between the member and handle and extending through said opening and connecting with the said body for facilitating the 35 movement of the body longitudinally of the housing.

MILES EDWARD BEVER.
